United States Patent Office

Des. 222,523
Patented Nov. 2, 1971

222,523

PAIR OF SKI GOGGLES

Terry J. Simpkins, Dublin, Ohio, and James P. Soroos,
New Haven, Conn., assignors to Bausch & Lomb In-
corporated, Rochester, N.Y.

Filed July 13, 1970, Ser. No. 23,917

Term of patent 14 years

Int. Cl. D2—03
U.S. Cl. D2—234

FIG. 1

FIG. 2

Des. 222,523

PAGE 2

FIG. 3

FIG. 4

FIG. 5

FIG. 1 is a front view of a pair of ski goggles showing our new design;

FIG. 2 is a side elevational view thereof;

FIG. 3 is a top plan view thereof;

FIG. 4 is a bottom plan view thereof; and

FIG. 5 is a rear elevational view thereof.

The side not shown is substantially the same in appearance as the side shown.

We claim:

The new and ornamental design for a pair of ski goggles, substantially as shown and described.
